METHOD OF MAKING RAIL CARS

Francis M. Gunn, Chicago, Ill., assignor to Pullman-Standard Car Manufacturing Company, Chicago, Ill., a corporation of Delaware

Application February 26, 1941, Serial No. 380,694

5 Claims.

(Cl. 29—164)

This application is a continuation in part of the copending application of Francis M. Gunn, Ser. No. 307,143, filed December 1, 1939, and now Patent No. 2,291,621, granted Aug. 4, 1942.

Due to the extremely high speeds attained by passenger trains today, it is of considerable importance to reduce the wind resistance of the train to a minimum. Indentations, projections, and sharp corners extending outwardly on the surface of the car sides are very objectionable; and, as a result of considerable wind tunnel testing conducted in 1932 and 1933 and prior to that time on streamlined trains, it was definitely concluded that even the presence of rivet heads on the side of a car produces a substantial dragging effect due to the resistance of turbulent air.

Because of the desirability of reducing all irregularities along the car sides and in an effort to produce a smooth contour along the sides of the car to satisfy the ever increasing public demand for modern appearing equipment, the present invention is particularly valuable as it relates to the railway passenger car industry.

Some years ago, riveting was used almost exclusively in the construction of steel passenger cars, but today the use of welding is becoming more and more common, and on modern equipment the presence of rivet heads on the sides of the cars is rapidly becoming a thing of the past. Even though welding has been used for a number of years, the car sides still are marred by ripples and buckles in the side sheathing and welding impressions left after the welding operation has been completed. Many attempts have been made to hide these disfigurements by painting and other means, but their presence still can be detected.

It is one of the principal objects of this invention, then, to eliminate the buckles and welding scars on the outer surface of the car side, thereby greatly improving the outside appearance and making it possible to produce a greater streamlined effect.

In a girder type construction of the side frame of a car, the sheathing plays an important part in carrying the stresses. Because of this, it is extremely difficult to eliminate the ripples and buckles occurring in the side sheathing due to the presence of stresses. The present invention successfully eliminates these buckles and yet retains the plain streamlined appearance of the car.

Heretofore, in performing the welding operation on the outside of the car side, when attach-

ing the sheathing to the framing members, it has been necessary to use a special jig for each individual car design in order to locate the framing members for the welder. Electric eyes and other equipment have been employed for this purpose, and this necessitated building a new jig each time a newly designed car was being constructed. The present invention eliminates this objection and is a definite step toward simplification and reduction in construction costs.

In prior methods of constructing car sides, the expansion and contraction occurring in the sheathing during the welding operation have been resisted by the framing, resulting in the setting up of internal stresses in the side sheets, producing buckles.

Among the principal objects of the present invention are the following: Initially to remove all wrinkles and buckles in the side sheathing before applying the sheathing to the side frame and to maintain the sheet in a smooth, flat condition while the side frame and sheathing are being fastened together; and to prevent the setting up of initial stresses in the sheathing which result in the formation of wrinkles and buckles therein, thus making it possible to produce a finished car side which is smooth and entirely free from these unsightly surface irregularities.

The above constitute some of the principal objects and advantages of the present invention, and other objects will become apparent from the drawings and the following description, in which

Fig. 1 is an elevation showing two small side sheet panels to be used in fabricating the side sheathing, with the window opening cut in the letter board panel;

Fig. 2 is a plan view of the panel shown in Fig. 1 showing the stiffeners applied to the inner face of each panel;

Fig. 3 is a plan view of the panel shown in Figs. 1 and 2 welded together by a horizontal seam and a dotted line showing of a second adjoining panel unit welded to the first by a vertical seam;

Fig. 4 is a vertical transverse sectional view through the side frame and vertical jig showing the relationship of the various elements making up the side frame when mounted on the vertical jig;

Fig. 5 is a full assembly view of the sheathing for the entire car side welded into an integral sheet showing the stiffeners on the inner face. A portion of the sheathing is broken away at the center;

Fig. 6 is a side elevational view of the car side framing members welded together to form the

entire car side, a portion of the frame being broken away at the center;

Fig. 7 is an enlarged fragmentary side elevational view of the car side showing the relative positions of the framing members, stiffeners, and welded joints in the completed side;

Fig. 8 is a side elevational view of the side sheathing viewed from the outside;

Fig. 9 is a side elevational view of the completed car side viewed from the inside of the car;

Fig. 10 is a vertical sectional view taken through the completed car side showing the relative positions of the sheathing, framing members, and stiffeners;

Fig. 11 is a horizontal sectional view of a portion of the car side taken on the line 11-11 of Fig. 9;

Fig. 12 is a fragmentary plan view of a small side sheet segment placed on the spot welding jig;

Fig. 13 is an enlarged fragmentary longitudinal sectional view taken through the jig working surface and side sheet segment showing the side sheet with a stiffener in place and the positions of the electrodes prior to the application of electrode pressure;

Fig. 14 is an enlarged sectional view corresponding to Fig. 13 but showing the upper electrode exerting force on the stiffener and sheet in position for welding. The bowing of the sheet downwardly is exaggerated to more clearly bring out the process;

Fig. 15 is a fragmentary side elevational view of a jig showing the car side sheathing suspended from the top and also showing a longitudinal stretching device forming part of the jig for removing buckles in the sheathing;

Fig. 16 is a top plan view of the jig shown in Fig. 15; and

Fig. 17 is an enlarged vertical sectional view of the clamp taken on the line 17-17 of Fig. 15.

When constructing the car side, the sheathing and side frame are fabricated separately and are assembled when both have been cooled to atmospheric temperature and properly straightened.

The sheathing is made up of a plurality of relatively small sheet panels 15 and 16 (Fig. 1) reinforced and welded together to form a unitary sheet extending the full length and height of the car side frame. Panel 15 may be referred to as a segment of the letter board panel and sheet 16 as a segment of the usual girder sheet.

The first operation in constructing the side sheathing is to cut window openings 17 in the letter board panel, spacing them to conform to the particular design of the car under construction.

Each car side may be treated separately, and enough letter board panel sheets 15 and girder sheets 16 will be prepared to complete the sheathing for one car side.

After the window openings have been cut out of the individual sheets, a plurality of stiffening units 18 (Fig. 2) are welded to the inner face of both the letter board panel sheets and the small segments of the girder sheets. These stiffeners comprise a series of corrugations 19 pressed into a sheet, and they are cut to the required size before being welded to the sheet.

Referring to Fig. 12, a spot welding jig 50 is shown, having its bench top divided into two segments 51 and 52, spaced apart to provide a gap 53. For the purpose of illustration, a girder sheet 16 is shown on the working area with its inner face disposed upwardly, and a sheet of cor-

rugated stiffeners 18 is placed on the inner face of the side sheet with the corrugations bridging the gap 53. Beneath the sheet and in the gap is an arm 54 extending forwardly from the back 55 of the welding machine, and this arm supports a bottom electrode 56.

Referring to Fig. 13, it is to be noted that this bottom electrode is slightly lower than the upper surfaces of the work bench areas 51 and 52; and, when the side sheet 16 and the corrugated stiffener sheet 18 are straddling the opening 53 prior to the application of electrode pressure, they are substantially straight and are spaced from the lower electrode 56 with upper electrode 57 directly above the lower electrode.

As shown in Fig. 14, the upper electrode 57 is moved downwardly onto the inner surface of stiffener sheet 18, and then pressure is exerted, forcing the stiffener and side sheet downwardly against the lower electrode 56 to place the welding electrodes in position for performing the welding operation and bowing sheet 16 downwardly to place its outer surface in tension. With the parts in this position, the welding current is turned on and a spot weld made between the stiffener and side sheet; and then, upon raising electrode 57, the inherent resiliency in the corrugated stiffeners 18 aids in restoring the side sheet 16 to its normal flat position.

If during the welding operation the side sheet and stiffeners were held flat, on completion of the operation the tendency would be for the stiffeners to be bowed with their faces engaging the side sheet being concave. This is caused by the greater heat on this contacting face of the stiffeners due to the concentration of welding heat between the side sheet and the stiffeners. Because of the greater stiffness of the stiffeners as compared with the side sheet, this warpage in the stiffeners causes buckling in the side sheet to place in the outer surface undesirable concavities. In order to overcome this objectionable bowing, the sheets and stiffeners are initially bowed to place the outer surface of the sheet in tension, as previously described, so that, upon cooling of these members, they will be substantially flat or only slightly convex on the outer surface of the sheet. The amount of bowing required during the spot welding operation depends upon the material used as well as its thickness. It is important that the side sheet be held on the welding jig in such a manner that, during the welding operation and upon subsequent cooling, the sheet and stiffeners are as nearly flat as practicable; and, in order to insure against the presence of concavities in the outer surface of the sheet, it may be desirable to be somewhat liberal in determining the initial bow.

The reinforced small sheets are next placed with a letter board panel sheet 15 above and a girder sheet segment 16 below, as shown in Fig. 3, on a welding jig and butt welded together, as indicated at 23. This operation is performed by the use of arc welding, and is continued until all like units of letter board panel sheets and girder sheet segments 15 and 16, respectively, for one entire car side are completely welded together.

These units are then placed on a large jig adapted to accommodate the sheathing for an entire car side, and complementary units are placed side by side and welded together by means of a vertical butt weld 24, also accomplished by the use of arc welding. Thus the entire sheathing for the car side is integrally welded together.

into a single reinforced sheet extending the full length and height of the car side.

The sheet is then carried to a vertical jig, generally indicated at 25 in Fig. 4.

While the side sheathing is being fabricated as described, the side frame, generally indicated at 26 in Fig. 6, is being assembled on a framing jig. This frame comprises the usual side plate 27, window header 28, belt rail 29, and side sill 30, with a plurality of vertical side posts 31 suitably spaced throughout the length of the side frame. These various members are welded together, preferably by arc welding, as indicated at 32, and additional horizontal and vertical braces (not shown) may be employed if needed. When the frame has been completely welded together and cooled, it is straightened on a straightening jig and put into shape for receiving the side sheathing.

Before the sheathing indicated at 33 in Figs. 4 and 5 is mounted on the jig 25 (Fig. 4), the welding bead, formed by welding together the small side sheets as previously described, is ground flush with the sheets on the inside surface of the sheathing, and then it is placed in the vertical jig 25 with its outside face flush against a flat copper plate 34 forming part of the vertical jig. While the sheathing is being held in place against this copper plate, the car frame 26 is properly positioned against the inner face of the sheathing with the framing members fitting between the stiffeners in the proper manner, and a plurality of upper and lower clamps 35 and 35', respectively, are drawn tight to securely hold the sheathing and frame on the jig. These clamps may be of any suitable design or construction, but, for the purpose of illustration, a U-shaped clamping member 36 is employed with one leg 37 resting against a backing plate 38 of the jig and the other leg 38 resting against some part of the side frame, as, for example, the side sill 30, as in the case of the lower clamp shown in Fig. 4. Some suitable means, such as a bolt 40 with a nut 40', is used to tighten the clamp against the jig and the car frame.

The jig itself comprises a plurality of H beams 41, anchored to the ground, as indicated at 42, to which is rigidly secured a steel backing plate 38. The copper plate 34 previously described is bolted or otherwise affixed to the backing plate 38, and serves as a conductor for the welding current.

The side sheathing and frame are now mounted on the vertical jig and ready for the application of the welding electrodes for spot welding the side frame to the side sheathing. Referring to Fig. 7, these spots are applied to the vertical side posts, as indicated at 43, and are suitably spaced to attain the required strength and rigidity in the fastening. The spot welds are also applied to the horizontal framing members, and their spacing also is suitable for obtaining the required strength.

The finished product gives a smooth, plain appearance on the outside of the car, as shown in Fig. 8, with the car side entirely free from buckles or electrode impressions caused during the welding operation. The fact that the electrode pressure is applied from the inside on the car framing members in the spot welding operation and the outside surface is flush against the relatively smooth copper plate 34 (Fig. 4) makes it possible to entirely eliminate the welding scars on the outer face of the side sheathing.

By welding the stiffeners to the back of the

small side panels, it is possible to obtain a very flat reinforced sheet highly resistant to buckling before any expansion and contraction are allowed to occur in the sheet itself, so that, when these sheets are arc welded together in the manner described, these stiffeners resist any tendency to buckle which may be present. Also, by fabricating the side sheathing and framing separately and then welding them together after they have cooled to atmospheric conditions and have been properly straightened, one of the greatest causes for buckling in the side sheathing has been eliminated.

Previously it was the practice to weld the individual side sheets directly to the frame, and during cooling of these sheets, after the welding had been completed, the resulting contraction was resisted by the framing members, thus setting up internal stresses and causing ripples and buckles to form.

As shown in Fig. 6, the horizontal and vertical seams in the side sheathing are located as closely as practicable to the two framing members in the car side. This is the preferable location for these seams, although, obviously, if it is found desirable, the individual sheets may be cut to sizes different from those shown so that these seams will fall some place else in the car side.

When welding the stiffeners to the sheets, the welding electrode is applied to the stiffener itself so that any scars due to electrode pressure which may result are on the inner face of the stiffeners instead of being on the outer surface of the sheathing. These spots are located as near as possible to the bent edges of the stiffeners so as to minimize as much as possible any tendency to have the stiffeners pull away from the sheets.

The stiffeners are placed with the corrugations extending lengthwise of the car because of the needed additional strength in that direction due to the cumulative contraction caused by the welding heat. This contraction may be as much as three-eighths to five-eighths of an inch.

The large copper plate 34 in the welding jig serves as an electrical conductor behind the sheathing to conduct the welding current. The large surface of contact with the sheathing spreads over a large area the pressure due to the welding electrode pressure. This distribution of force prevents depressions from appearing in the outer face, thus preserving the smooth contour of the sheathing.

When building cars, it is customary to place an initial camber in the underframe, and, as the construction progresses and weight is loaded onto the underframe, this camber straightens out. Before welding the side frame onto the sheathing in the present process, an initial camber is placed in the sheathing and the side frame, which also straightens out as the car shell is loaded. This may be done by filing the opposite edges of the units made up of letter board panel sheets and girder sheet segments 15 and 16 transversely of the car side, so as to taper these units slightly toward their lower edges so that, when units are welded together side by side, the initial camber is present.

As shown in Figs. 15 to 17, inclusive, the side sheathing 33 is held in place on the jig by supporting members 60 mounted at the top of the jig. These supporting members each comprise a pair of inverted U-shaped clamps 61 and 62 having a spacer 63 (Fig. 17) secured to legs 64 and 65 of each clamp. When the clamp is in place, legs 64 and 65 straddle the steel and copper

plates 38 and 34, respectively, with the spacer 63 resting on the top of these plates. Extending across the tops of the inverted U-shaped clamps 61 and 62 are a pair of plates 66 and 67 mounted in an upright position and spaced to provide an opening therebetween to receive a hook 68 (Fig. 17), which passes downwardly between plates 66 and 67, terminating in the hooked portion 68'. The top of the hook 68 is threaded to receive a nut 69, and a washer 70 is placed between the nut and the plate members 66 and 67 so that the hook is supported on the tops of these plates, and its height may be adjusted by turning the nut 69. Straps 71 are welded, as indicated at 72 (Fig. 15), or otherwise secured along the top of the side sheathing 33, and hook 68 on each supporting member 66 hooks through an opening 73 in one of the straps 71 for supporting the sheathing. An adjustable screw 65' (Fig. 17) passes through leg 65 of each U-shaped clamp, and serves to secure the clamp to the top of the jig.

Along the opposite vertical edges of the sheathing are a plurality of straps 74, welded or otherwise secured to the sheathing 33, and each strap is provided with a hole 75 adjacent to its outer end. These straps 74 are provided for the purpose of connecting a stretching device to the sheathing 33 so that the sheathing can be stretched in a general longitudinal direction.

Some means for supporting the stretching device must be provided, and, for the purpose of illustration, two suitable means are shown. Referring particularly to Fig. 16, at the left side thereof an anchor beam 76 is mounted on the floor or in the ground, and the stretching device, generally indicated at 77, is fastened to this anchor beam by means of an angle bar 78. This anchor beam 76 serves as a support for the stretching device. At the right side of the same figure, a second support is shown, which includes a bracket 79 made up of an irregularly shaped plate 80 extending to the rear flange 81 of the I-beam 41 forming part of the welding jig. A plate member 82 extends from the front flange 83 of the I-beam 41, and is welded to the irregularly shaped member 80 to serve as a compression member in the bracket 79. The stretching mechanism, generally indicated at 84, is supported by the bracket 79.

After the side sheathing 33 is mounted on the jig and the nuts 69 are properly adjusted so as to hang the sheathing 33 in the proper manner and with the least possible number of ripples therein, the stretching mechanism is attached to the opposite ends of the sheathing. At the left side of the jig shown in Fig. 15, this mechanism comprises the I-beam 76, a floating or equalizing beam 85, a pair of rods 86 hooked to the beam 85 and secured at their opposite ends to the angle member 78 by means of nuts 87 threaded onto the ends of rods 86, and a plurality of turn buckles 88 secured to the floating beam 85 and provided with hooks 88' adapted to grasp one of the straps 74 through its opening 75. Reinforcing angles 89 and 90 (Fig. 16) are provided on the opposite sides of the floating beam 85 to stiffen the beam.

On the right-hand side of the jig shown in Fig. 15, a stretching device includes the bracket 79 attached to the I-beam 41 and the turn buckles 91 hooked to the outer ends of straps 74 and carried by the brackets 79. A nut 92 is threaded onto the free end of each turn buckle

91, and a washer 93 is inserted between the nut and the bracket.

When the various turn buckles are hooked in place through the ends of their respective straps 74, they are tightened to distribute the stretching in the desired manner. Because of the presence of window openings 17 and other cut-outs in the side sheathing, it is desirable to adjust the turn buckles so that the stretching is concentrated above and below these openings, so that in the zone of these openings the sheathing is stretched to a much lesser degree. This is done to avoid localization of stresses in the regions of the windows. The adjustment is made by initially setting the numerous turn buckles 88 and 91 on the two ends of the sheathing to properly distribute the stretching forces. After the stretching mechanism is adjusted to the desired degree, the remainder of the stretching is accomplished by tightening nuts 87 on the ends of rods 86, so that a pulling force is placed on the floating beam 85, which, in turn, applies a pulling force on each of the turn buckles 88, thereby stretching the side sheathing the desired amount.

It is to be noted that the turn buckles 88 and 91 are pitched from a true horizontal position, so that those above the longitudinal center line of the sheathing are inclined upwardly, whereas those below are inclined downwardly. In this manner, vertical components are present in each of the stretching forces applied to the sheathing 33, thereby making it possible to remove any horizontal ripples which otherwise may result if the stretching forces were applied in a true horizontal direction. This inclination of the turn buckles serves further to avoid localization of stresses around the window openings.

When the stretching of the side sheathing is employed as one step in the fabrication of the car side, this stretching operation is performed after the side sheathing is made into an integral member and before the side framing members are welded to the sheathing. The welding operation employed in connecting together the sheathing and the framing members is performed during the time the sheathing is being stretched, so that these framing members tend to maintain this stretched condition in the sheathing after the welding operation has been completed.

It has been found that the method of construction described herein greatly improves the outer appearance of car sides. It is possible to remove buckles and ripples to the extent that they are not visible to the naked eye. Thus, a problem which has confronted car builders for years has finally been solved.

A specific embodiment of the present invention has been selected for the purpose of disclosure as required by section 4888 of the Revised Statutes; but, obviously, many changes and modifications may be made, some of which have been suggested, without departing from the spirit of the invention. No attempt has been made to accurately show the location of the spot welding throughout the car side. The spacings between the spots will vary according to individual requirements.

70 I claim:

1. The method of fabricating a vehicle wall having a frame covered by sheathing, the frame engaging substantially the entire perimeter of the sheathing, comprising forming a plurality of flat, metal sheets, then making integral with each

sheet stiffeners reinforcing the major area thereof for resisting deformation of the sheets arising from the subsequent welding operations, leaving portions of the sheets free of stiffeners to accommodate framing members, then welding together the adjacent edges of the stiffened sheets while maintaining said sheets in substantially the same plane and making the welds substantially continuous throughout the lengths of the edges to form the sheathing for the wall, then removing ripples by tensioning the sheathing from the opposite ends thereof substantially uniformly throughout the extent of the sheathing and while so tensioning the sheathing welding thereto throughout substantially the entire perimeter of the sheathing the frame applied with the framing members against the said stiffener-free areas of the sheathing.

2. The method of fabricating a vehicle wall having a frame covered by sheathing, the frame engaging substantially the entire perimeter of the sheathing, comprising forming a plurality of flat, metal sheets, then making integral with each sheet stiffeners reinforcing the major area thereof for resisting deformation of the sheets arising from the subsequent welding operations, leaving portions of the sheets free of stiffeners to accommodate framing members, then welding together the adjacent edges of the stiffened sheets while maintaining said sheets in substantially the same plane and making the welds substantially continuous throughout the lengths of the edges to form the sheathing for the wall, then removing ripples from the sheathing and while holding the sheathing in a substantially smooth, ripple-free condition welding thereto throughout substantially the entire perimeter of the sheathing the frame applied with the framing members against the said stiffener-free areas of the sheathing.

3. The method of fabricating a railway car side wall having a frame made up of framing members including a side sill, a side plate, a pair of end posts, all interconnected by intermediate framing members, said frame being covered by sheathing consisting of a plurality of letter board and girder sheet panels and engaging substantially the entire perimeter of the sheathing made up of a plurality of letter board and girder sheet panels, comprising making integral with each of said panels stiffeners reinforcing the major area thereof for resisting deformation of the sheets arising from the subsequent welding operations, leaving marginal and intermediate portions of the sheets free of stiffeners to accommodate the said framing members, then welding together the adjacent edges of corresponding stiffened letter board and girder sheet panels while maintaining said panels in substantially the same plane thereby forming a plurality of flat, stiffened sheets, and then welding together the adjacent edges of the said flat, stiffened sheets making the welds substantially continuous throughout the lengths of the edges to form the sheathing for the wall, then removing

ripples from the sheathing and while holding the sheathing in a substantially smooth, ripple-free condition welding thereto throughout substantially the entire perimeter of the sheathing the frame applied with the framing members against the said stiffener-free areas of the sheathing.

4. The method of fabricating a vehicle wall having a frame covered by sheathing, the frame engaging substantially the entire perimeter of the sheathing, comprising forming a plurality of flat, reinforced, metal sheets by placing against the inner face of each of a plurality of flat, metal sheets stiffeners adapted to reinforce the major area of the sheet against deformation arising from the subsequent welding operations but leaving portions of the sheets free of stiffeners to accommodate framing members, then uniformly bowing both the stiffeners and the sheet within their elastic limits so that the outer face of the sheet is in tension, and while so maintaining them welding them together by applying welds over a substantial portion of the area of the stiffeners, then allowing the sheet and the stiffeners to return to their original flat condition, then welding together the adjacent edges of the stiffened sheets while maintaining said sheets in substantially the same plane and making the welds substantially continuous throughout the lengths of the edges to form the sheathing for the wall, then removing ripples from the sheathing and while holding the sheathing in a substantially smooth, ripple-free condition welding thereto throughout substantially the entire perimeter of the sheathing the frame applied with the framing members against the said stiffener-free areas of the sheathing.
5. The method of fabricating a vehicle wall having a frame covered by sheathing, the frame engaging substantially the entire perimeter of the sheathing, comprising forming a plurality of flat, metal sheets, then making integral with each sheet stiffeners reinforcing the major area thereof for resisting deformation of the sheets arising from the subsequent welding operations, leaving portions of the sheets free of stiffeners to accommodate framing members, then welding together the adjacent edges of the stiffened sheets while maintaining said sheets in substantially the same plane and making the welds substantially continuous throughout the lengths of the edges to form the sheathing for the wall, then removing ripples by tensioning the sheathing from the opposite ends thereof substantially uniformly throughout the extent of the sheathing by applying tension forces having components thereof directed longitudinally and in a direction corresponding to the height of the sheathing and while so tensioning the sheathing welding thereto throughout substantially the entire perimeter of the sheathing the frame applied with the framing members against the said stiffener-free areas of the sheathing.

FRANCIS M. GUNN.
